UNITED STATES PATENT OFFICE.

JOHN LARSON, OF LITTLEFORK, MINNESOTA.

CLOTHESPIN.

Application filed September 21, 1925. Serial No. 57,835.

This invention relates to improvements in clothes pins and its object is to provide a clothes pin that is simple in construction, positive and efficient in operation and cheap to manufacture.

A further object is to provide a clothes pin adapted to obtain a maximum purchase upon the garment and in garments of medium or large size to obtain a double purchase or grip upon the same.

With the foregoing and other objects in view the invention consists in the combination and arrangement of parts to be herein-after fully described, pointed out in the appended claim and illustrated in the accompanying drawing which forms a part of this application and in which—

Fig. 1 is a plan view of the clothes pin.

Fig. 2 is a view in side elevation illustrating its application.

Fig. 3 is an inverted view of the pin showing how it may be suspended from the line when not in use.

Like reference characters denote corresponding parts throughout the several views.

The clothes pin is formed of a single piece of material, preferably wire, the ends of which are bent to form tiny eyes 1, 2 more for ornamentation than otherwise. The material extending from the eye 2 is curved or bent to form an enlarged hook 3 which merges into the side member 4. The material from or beyond the eye 1 forms the side member 5 which is of greater extent than the side 4, said sides being spaced but a very slight distance apart, parallel to each other, and waved symmetrically, said sides being united by the loop 6, the hook 3 adjacent the eye 2 being spaced very slightly from the side member 5.

The clothes pin is applied to the clothes line 7 by manually spreading or pressing the hook 2 and side member 4 away from the side member 5 until the line can be disposed in the loop 6. When a garment 8 is to be secured to the line with the clothes pin the pin is again spread apart to receive the garment or garments, the sides 4 and 5 of the clothes pin coming together against the garment for almost their entire length thus obtaining a purchase or bite upon the garment and the hook 2 and side 5 also engaging the garment beyond its point of engagement by both of said sides thus affording a positive and double purchase or bite of the pin upon the garment.

When the clothes pin is not in use it may be suspended from the clothes line by inverting it and permitting disposal of the line through the hook 2 as shown in Fig. 3.

What is claimed is—

A clothes pin formed of a single piece of resilient material comprising a pair of spaced non-crossed side members forming elongated jaws adapted to come together upon the garment, a loop connecting said side members and receiving the garment and the clothes line, and an enlarged hook at the end of one of said side members, the free end of said hook being contiguous to the other side member and forming jaws together therewith, the bite of said jaws being in spaced relation to the aforesaid elongated jaws, the entire space between said jaws forming a mouth for said hook whereby the clothes line is admitted to said hook when the same is not in use upon a garment.

In testimony that I claim the foregoing as my own I have hereto affixed my signature.

JOHN LARSON.
